Attorney.

UNITED STATES PATENT OFFICE

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI

ANCHOR

Application filed November 5, 1923. Serial No. 317,271.

This invention relates to anchors, and with regard to certain more specific features to helical earth anchors and wrenches therefor.

Among the several objects of the invention may be noted the provision of a stronger helical anchor (and wrench therefor) adapted to be driven home or retrieved by turning it with the wrench; and the provision of an anchor of the class described having no extraneous driving lugs or the like which are weak and difficult to properly manufacture. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a side elevation showing the anchor and wrench therefor in driving position.

Fig. 2 is a fragmentary section showing the assembled anchor and wrench;

Fig. 3 is a fragmentary side elevation of the gripping end of the wrench.

Fig. 4 is a cross section taken on line 4—4 Fig. 2; and

Fig. 5 is a cross section taken on line 5—5 of Fig. 2.

Similar reference characters indicate corresponding parts throughout the several views of the drawings.

Referring now more particularly to Fig. 1, there is illustrated at numeral 1 a body portion of an anchor, including a helical web 5 and an upper head 3 adapted to be connected with an anchor rod 7. The helical web and certain other features have been previously disclosed by myself, but what is deemed to be new in this anchor is the connection between the head portion 3 and the rod 7.

It will be seen from Fig. 1 that the rod 7 comprises a length of tubing, part of which is round, as indicated at numeral 9 and part 50 of which is square or polygonal as indicated

at numeral 11, the square or polygonal portion being adapted to slidably receive a wrench 13 for applying torque.

With the contrivances heretofore used, the tube of the wrench has been notched and made to engage with a lug or the like on the anchor head or on the anchor itself. Either a single notch and lug was used or a plurality. However, in either case provision was never made for surrounding and bracing the lower end of the tube 9. The result has always been that when somewhat large twisting loads are applied to the tube, there is a tendency for the lower end to deform from its circular contour and once the deformation has started, it quickly proceeds to a complete breakdown of the tube by way of tearing along a helical path. The maximum load which the tube was thus able to withstand was much less than its twisting strength.

In order to avoid the above difficulties, I form tenons 15 at the lower end of the tube in castellated fashion as indicated in Fig. 3 which shows the tenons 15 and recessed portions 17 therebetween.

The head 3 of the anchor is hollow and adapted to receive the lower end of the anchor rod 19. At the top of the head 3 and around the opening 21 is formed an annular recess 23. This recess is annularly spaced from the hole 21. The bottom of the recess 23 is formed with downwardly extending recesses 25 which accommodate said extending portions 15 of the wrench 7 (see Figs. 3, 4 and 5). In other words, the bottom of the annular recess 23 comprises a mortise which accommodates a tenon of the wrench 7. The result is that the extension 15 fitting in the recesses 25 serves to drive the anchor through the earth, while the annular recess 23 surrounds the endward solid region 27 of the wrench so as to support this region throughout. The result is that any tendency of the extensions 25 to strain the region 27 out of its circular shape is prevented. The failure, if any, must be by shearing off of the extensions 15, rather than by having said extensions start incipient tearing into the region 27 at the corner portions 29; or having said extensions start an incipient bending at said region 27. After 100

the anchor is set the wrench may be withdrawn upwardly, and removed from over the anchor rod 19.

It will be noted from Figs. 3 and 5, that the 5 edges of the extensions 15 are somewhat undercut. The edges of the depressions 25 are likewise treated so as to give a positive grip during driving. It is to be understood that the widest portions of the extensions 15 are 10 adapted to pass through the narrowest portions of the recesses 25.

The term "annular" is herein to be construed as applying to shapes which are hollow, including circular, ovate and polygonal 15 ones.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. The connection between an earth anchor and its wrench comprising a head on the anchor, means for fastening an anchor rod into 30 said head, an annular recess spaced from and surrounding said means, a mortised bottom in said recess, and tenons at the end of said wrench adapted to fit said mortised bottom.

2. The connection between an earth anchor 35 and its wrench comprising a head on the anchor, means for fastening an anchor rod into said head, a circular recess spaced from and surrounding said means, a mortised bottom in said recess, and tenons at the end of said 40 wrench adapted to fit said mortised bottom for driving purposes, said circular recess engaging such a substantial portion of the circular regions of the wrench that the latter are braced against deformation when the 45 anchor is twisted by the wrench.

3. The connection between an anchor and its tubular wrench comprising a head on the anchor, an annular recess in said head for accommodating said tubular wrench, mortised 50 portions in the bottom of the recess and tenons at the end of the wrench adapted to engage said mortised portions of the head, the annular recess engaging a substantial portion of the completely circular regions of the 55 wrench so as to brace them against deformation and breakage.

4. The connection between an earth anchor and its wrench comprising an annularly recessed head on the anchor, an annular portion 60 on the wrench engaging said recessed portion, the bottom of the recess and the end of the annular portion on the wrench being adapted to effect driving contact.

5. The connection between an earth anchor 65 and its wrench comprising an annularly re-

cessed head on the anchor, means for fastening an anchor rod into said head within the confines of the recess, an annular portion on the wrench engaging said recessed portion, said annular portion surrounding the anchor rod and the bottom of the recess and the end of the annular portion on the wrench being adapted to effect driving contact.

In testimony whereof, I have signed my name to this specification this 1st day of November, 1928.

THEODORE BIRKENMAIER.
